UNITED STATES PATENT OFFICE.

CHARLES W. BECK, OF DETROIT, MICHIGAN.

OIL-CAN HOLDER.

1,158,361.

Specification of Letters Patent. Patented Oct. 26, 1915.

Application filed September 17, 1914. Serial No. 862,126.

To all whom it may concern:

Be it known that I, CHARLES W. BECK, a citizen of the United States, residing in the city of Detroit, county of Wayne, and State of Michigan, have invented certain new and useful Improvements in Oil-Can Holders, of which the following is a specification.

The object of this invention is to provide an oil can holder of very simple construction adapted to be secured in any desired position upon an automobile to conveniently hold an oil can.

The can holding means is designed to yield readily to permit the can to be detached quickly by a pull thereon.

In the drawing, Figure 1 is a perspective view of the holder, an oil can being shown therein in dotted lines; Fig. 2 a plan view of the holder; Fig. 3 a bottom view thereof; 20 and Fig. 4 a rear end view.

Referring to the various parts by numerals, 1 designates the main body or plate of the holder, said plate being formed of sheet metal, stamped or pressed into shape. This 25 main plate is formed with screw holes 2, through which may be passed suitable attaching means. A portion of the main plate is stamped upwardly to form the integral can-holding lug 3. Near the outer end of 30 the main plate 2, lugs 4 are stamped out and bent downwardly to form two stops, one of said stops being at the forward end of the main plate and the other being at the left-hand side thereof. This main plate is also 35 formed with an aperture 5 near its forward end, for a purpose which will be hereinafter set forth.

Rigidly secured to the upper side of the main plate is the forwardly and outwardly 40 extending can-holding arm 6, the outer end of which is formed with an upstanding inwardly inclined can-holding lug 7. This arm is also formed with a downwardly extending lug 8, which passes through the aperture 5 in the main plate and is then bent 45 outwardly to form a hook which rigidly holds the arm 6 in position. The inner end of said arm is rigidly secured to the main plate by means of a pin 9. It is manifest 50 that the rigid hook 8 holds the arm 6 against pivotal or swinging movement. Arm 6 is also provided with an outwardly extending lug 10 to which one end of the spring 11 is connected.

55 Pivottally secured to the under side of the main plate is a swinging arm 12, said arm

being secured in position by means of the pin 9, as shown in Fig. 3. This arm 9 is bent upwardly as at 13 to bring the outer portion thereof into the same horizontal plane as the body of the arm 6 as shown clearly in Fig. 4; and the outer end of this swinging arm is bent upwardly to hold the can-holding lug 14. This arm extends outwardly between the depending lugs 4 and its pivotal movement is limited, said lugs acting as stops. This arm 12 is formed with the depending lug 15 to which one end of the spring 11 is connected, said spring serving to normally hold said arm against one of the stops 4. The tension of the spring need only be sufficient to hold the can in place and to yield readily when the arm 12 is swung outwardly to release the can.

75 From the foregoing, it is manifest that I provide a very simple can holder, which may be very cheaply manufactured.

What I claim is:

1. An oil can holder comprising a main 80 supporting plate having an upwardly extending integral can-holding lug, and two depending integral stop lugs near its forward end, a pivoted can-holding arm secured to the under side of the main plate 85 and arranged to swing between the two stop lugs, the outer end of said arm being turned upwardly to form a can-holding lug, a rigid can-holding arm secured to the top of said plate and formed with a lug ex- 90 tending downwardly through an aperture in the main plate, the outer end of said rigid arm being turned upwardly to form a can- holding lug and a spring connected to adjoining edges of the can-holding arms and normally holding the pivoted arm against one of the stop lugs.

2. An oil can holder comprising a main supporting plate formed with an integral upwardly extending can-holding lug and 100 two downwardly extending integral stop lugs, a pivoted can-holding arm secured to the under side of said main plate and adapted to swing between the two stop lugs, the outer portion of said arm being bent upwardly and lying in a plane parallel with the plane of the upper surface of the supporting plate, a rigid can holding arm secured to the top of the main plate and 105 formed with an integral downwardly extending lug, said lug passing through the main plate and holding the said arm against 110

pivotal movement, the outer ends of said arms extending upwardly and inwardly to form can-holding lugs and a coil spring connected to the can-holding arms and 5 yieldingly holding the pivotal arm against one of the stops.

3. An oil can holder comprising a main supporting plate provided with an upwardly extending can-holding lug and two 10 downwardly extending stop lugs, a pivoted can-holding arm secured to the under side of said main plate and adapted to swing between the two stop lugs, the outer portion of said arm being bent upwardly and lying 15 in a plane parallel with the plane of the upper surface of the supporting plate, a rigid can-holding arm secured to the top of the main plate and provided with downwardly extending means, said means engaging the 20 main plate and holding the said arm against pivotal movement, the outer ends of said arms extending upwardly and inwardly to form can-holding lugs and a coil spring connected to the can-holding arms and yieldingly holding the pivotal arm against one 25 of the stops.

4. An oil can holder comprising a main supporting plate having an upwardly extending can holding lug and two stop lugs 30 near its forward edge, a rigid can holding arm carried by said main supporting plate the outer end of said rigid arm being turned upwardly to form a can holding lug, a pivoted can holding arm secured to the main

plate and arranged to swing between the 35 two stop lugs, the outer end of said arm being turned upwardly to form a can holding lug and the upper surface of said pivoted arm being in substantially the same horizontal plane as the supporting surface of 40 the rigid can holding arm, and a spring connected to the pivoted arm and to the rigid arm and normally holding the pivoted arm against one of the stop lugs.

5. An oil can holder comprising a main 45 supporting plate having an upwardly extending can-holding lug and two stop lugs near its forward edge, two can-holding and supporting arms extending forwardly and outwardly from the forward edge of the 50 main plate, the outer ends of said arms being turned upwardly to form can-holding lugs and the can-engaging and supporting surfaces of said arms being in substantially the same horizontal plane, a pivot for one 55 of said arms near the forward edge of the main plate said pivoted arm swinging between the two stop lugs, and a spring connected to said pivoted arm and to a rigid part whereby said spring holds the arm 60 against one of the stop lugs.

In testimony whereof I hereunto affix my signature in the presence of two witnesses.

CHARLES W. BECK.
